YARN FEEDING MECHANISM FOR
STRAIGHT KNITTING MACHINESMax Richter, West Reading, Pa., assignor to
Textile Machine Works, Wyomissing, Pa., a
corporation of Pennsylvania

Application May 21, 1935, Serial No. 22,537

18 Claims. (Cl. 66—126)

My invention relates to novel driving mechanisms for the carrier rods of full-fashioned knitting machines, and particularly to means for automatically connecting the rods to, and releasing them from, the carrier-rod actuator rod in accordance with the patterns of hosiery being knitted.

The usual drive for yarn carrier rods includes a longitudinally reciprocable friction-box rod carrying a plurality of friction boxes which are connected to the carrier rods. The stroke of the friction or actuator rod is constant, and it may move independently of a friction box and its carrier, while the latter is held inoperative. This action occurs when the strokes are maintained constant, and when the fabric is progressively narrowed, following which action corresponding-ly decreasing strokes of the carriers are required.

Likewise, during plating or splicing operations, certain of the carriers move only a small fractional part of the distance traversed by the friction rod. Consequently, to maintain the correct lead of the carrier relative to the sinkers, during plating, and while the fabric is gradually decreased in width, independent means must normally be provided to hold the carriers inoperative until the selected sinkers have been advanced, whereupon the carriers are released by the independent means, and permitted, with the friction boxes, to be actuated by the friction-box-rod.

It accordingly, is an object of the invention to provide a novel rod-operating mechanism for a full-fashioned knitting machine that shall operate the carriers with a constant lead with respect to the sinkers, irrespective of the rod travel.

Further, although automatic rod-operating mechanisms, of the rotary-type, have heretofore been known in the art, as set forth in my Patent No. 1,884,244, issued October 25, 1932 and assigned to the assignee hereof, to the best of my knowledge, no means has heretofore been devised whereby the rod-operating mechanism will likewise control the lead of the carriers relative to the sinkers, during the couloring operation.

It is another object of the invention to automatically control the carrier rods of a full-fashioned knitting machine in accordance with a pattern, by the employment of a rotary friction-box or clutch mechanism and, at the same time, maintain a correct lead of the carriers relative to the sinkers.

Also, it has heretofore been suggested to provide an auxiliary pattern-control unit for each of several knitting operations, and to control such units by a main or master pattern chain, the

auxiliary unit being operated from the main cam shaft of the machine through a constantly operating linkage, and selected for such operation by the main pattern chain, through another linkage, this construction, whereby two linkages are employed, resulting in an undue number of parts, excessive weight and unnecessary wear.

It is therefore, another object of the invention to provide a device, in association with a friction-drive mechanism, as herein set forth, for avoiding such objections by a single linkage, between the cam shaft and the main pattern device, on the one hand and the auxiliary pattern units on the other hand, whereby there are no constantly operating parts, no undue number of parts or excessive weight and cost, no unnecessary wear, and none of several adverse effects resulting from such mechanism.

Another object resides in the provision of the auxiliary pattern units in the form of variable-link chains, whereby changes in the adjustment and operation of the machine may be effected quickly and at low cost.

A further object of the invention is to provide a device of the above indicated character that shall be simple and durable in construction, economical to manufacture and effective in its operation.

With these and other objects in view, which will be apparent from the following description of the illustrative embodiment of the improvement shown in the accompanying drawings, the invention resides in the novel elements and combinations thereof, as hereinafter more particularly set forth in the claims.

In the drawings:

Figure 1 is a plan view of one end portion of a full-fashioned knitting machine embodying my invention;

Fig. 2 is a view, in rear elevation, of a portion of the machine indicated in Fig. 1;

Figs. 3 and 4 are plan views, similar to a portion at the lower left-hand corner of Fig. 1, illustrating the application of one of the devices embodied in the invention, as applied to each of the carrier rods of a machine employing eight such rods;

Fig. 5 is a cross sectional view, taken substantially along the line 5—5 of Fig. 1;

Fig. 6 is an enlarged cross-sectional view, taken substantially along the line 6—6 of Fig. 2;

Fig. 7 is a view, on an enlarged scale, of the device of the invention, as shown at the top of Fig. 6;

Fig. 8 is a view of the structure, taken sub-

- stantially in the direction of the arrow A of Fig. 6;
- Fig. 9 is a rear elevational view of the device, taken substantially along the line 9—9 of Fig. 8;
- 5 Fig. 10 is a detail view of certain of the mechanism shown in Fig. 6;
- Fig. 11 is an enlarged detail view of a portion of an auxiliary pattern-control unit embodied in the invention;
- 10 Fig. 12 is a further enlarged top plan view of a section of a pattern chain of the device of Fig. 11;
- Fig. 13 is a view, in side elevation, of the chain structure of Fig. 12;
- 15 Figs. 14 to 17, inclusive, are diagrams illustrating successive steps in the operation of a rotary friction drive device between the actuator rod and a carrier rod during the knitting of one portion of a stocking; and
- 20 Figs. 18 to 21, inclusive, are diagrams similar to those of Figs. 14 to 17, illustrating corresponding steps in the operation of corresponding parts during the knitting of another portion of the stocking.
- 25 Figs. 1, 2 and 5 illustrate various parts of a "Reading" full-fashioned knitting machine embodying the mechanism, and elements of my invention, which, for clearness, only those parts of the various mechanisms necessary for an understanding of the invention are illustrated; the other parts, and the operation thereof, being well known in the art, as fully shown and described in the "Reading" full fashioned knitting machine catalogue, copyright 1929, and published by the Textile Machine Works, Reading, Pennsylvania.
- Referring to the drawings, a rotatable cam shaft 10, supporting the cams employed to operate the various mechanisms, is supported by end 40 and center frames 12 and 13, respectively, which are connected by transverse tie members, including a front beam 14, a back beam 15, a front bed 16, and a center bed 17; constituting a structure upon which the operating parts of 45 the machine are supported. Shiftable cams 18 and 19, cooperating with a main pattern device or chain motion mechanism C, constitute means whereby the cam shaft 10 may be shifted from its normal knitting position to its narrowing 50 position for operating narrowing heads N in a usual manner.
- The rotative movement of the cam shaft 10 is translated into the reciprocative motion of slurcock cams 20, by an intermediate coulier cam 22, Fig. 2, which is connected to the cam shaft 10 through bevel gearing (not shown), to reduce the rotative speed, from the cam shaft 10 to the coulier cam 22, in the ratio of two to one. The coulier cam 22, coacting with rollers 23 on a pitman 24, reciprocates the pitman and a base 25 for an actuator rod 26, corresponding to a usual friction rod, through an intermediate rocker arm 27 and a connecting link 28, in a usual manner.
- 65 The pitman 24 is pivotally supported, at one end, by a short rocker arm 29 supported from the back beam 15, by a bearing 30, and at the other end is connected to the rocker arm 27, which is pivotally connected by a shaft 33 to a bearing 32 secured to the back beam 15. The reciprocatory movement of the base 25 is transmitted to the slurcock cams 20 through an intermediate slide box 34, which is joined to a connecting bar 35 on which are secured slide boxes 36, maintaining the cams 20.
- During the reciprocative travel of the slurcock cams 20, jacks 37 are impelled thereby to move sinkers 38 between needles 39, for sinking the yarn fed by carriers 40. The carriers 40 are secured to carrier rods 1 to 8, inclusive, which are slidably mounted in brackets 43 on the center bed 17. The carriers 1 to 8, inclusive, are provided with toothed racks 1^a to 8^a, inclusive, respectively, Figs. 3 and 4. Retraction of the sinkers and dividers is effected by a catch bar 44, which is operated by cams on the shaft 10; the operation of the needles being effected through a needle lever 45, and a presser lever 46, which are actuated by cams on the shaft 10.
- In accordance with the invention, instead of the usual friction boxes, a plurality of connectors F¹ to F⁸, inclusive, as best seen in Figs. 3 and 4, are provided to separately operate a corresponding number of carrier rods. The connectors F¹ to F⁸, inclusive, are supported by certain of back 20 narrowing shaft bearings 47, and carrier rod brackets 43, as indicated in Figs. 5, 6 and 7. To each bracket 43 is bolted a frame 48 of one of the connectors F¹ to F⁸, the front end of the frame being supported by members 49 secured to the 25 carrier brackets 43, as indicated in Fig. 5. Rotatably mounted in the bearings of the frame 48, as indicated in Figs. 6 and 7, is a shaft 50, to which a gear wheel 52 is fixed for cooperation with a toothed rack 1^a on the carrier rod 1, which the unit F¹ is to actuate; the gear wheels 52 of the units F² to F⁸, inclusive, similarly being provided for cooperation with toothed racks 2^a to 8^a, respectively to Fig. 3.
- Rigidly secured to the shaft 50, is a sleeve 54, Fig. 7, having a raised portion 55 between a driving gear 56 and a driving disc 57 of the carrier friction driver D, Figs. 6 and 7. The disc 57, which forms the base for the driver D, has a hub portion 57^a extending from the internal face 40 thereof, which is rotatably mounted on the sleeve 54, and is axially movable relative thereto. Its axial position is controlled, by a lever 58, through the abutting surfaces 57^a and 58^a and 57^b and 58^b respectively.
- 55 An external disc 59, held by a key 60 against turning relative to the driving disc 57, and constituting one element of a slip, yielding, or friction clutch, is axially movable relative thereto. Similarly, a center disc 62, constituting another element of the slip clutch, held against rotation relative to the disc 59 by a key 63, is axially movable with respect thereto. The friction, or slip-clutch plates 64 and 65, provided on both sides with facings 64^a and 65^a, respectively, of leather or other suitable material, are rotatably mounted on the hub portion 62^a of the center disc 62, and are held in frictional engagement with opposite faces of the disc 62, as well as with the inner faces of the discs 59 and 57, through the compressing action exerted on the disc 59 by a coil spring 66. The degree of compression of the spring 66 is controlled by adjustable lock nuts 67 on the hub 57^a, as seen in Figs. 6 and 7.
- To the driving disc 57 is secured a tooth element 68, constituting one element of a lock clutch, which, when the device is operated, coacts with one of the recessed elements 69, constituting a cooperating element of the lock clutch, in the side of the driving gear 56. Thus, when the gear 56 is rotated, by its coacting rack gear portion 70 of the member 26, moving in accordance with movement of the rocker arm 27 to which it is connected, the driving disc 57 is rotated by the co- 75

operating lock clutch elements 68 and 69, whereupon the friction discs 64 and 65 are rotated.

Ears or lugs 64^b and 65^b, Figs. 8 and 9, extending from the friction plates 64 and 65, respectively, and consequently, rotating in conjunction therewith, engage opposite sides of the lever 58, the ear 64^b engaging, and rotating the lever 58, when the driver D is rotated in a clockwise direction, see Fig. 9, by a stroke to the left of the actuator rod 26, Fig. 2. Reverse movement of the actuator rod 26 will bring the ear 65^b into engagement with the lever 58 and impart a counterclockwise movement thereto, to move the carrier rod 1 to the right, through the intermediate shaft 59, the gear wheel 52 and the rack gear 1^a.

The lever 58 is secured to the shaft 59 by a feather key 12, thereby permitting axial shifting of the lever 58 relative to the shaft 59, while every rotative movement of the latter is directly transmitted to the lever 58. Since the rack gear 1^a, on the carrier rod 1, is in continuous engagement with the gear 52 secured to the shaft 59 by a set screw 13, every rotative movement of the lever 58, will actuate the corresponding carrier rod.

When the stroke of the carrier rod is terminated by any of the well known stop mechanisms, such as a stop 71 of the narrowing head N, Fig. 1, the lever 58 is prevented from further rotation, and stops the friction plate which is, at that time, in operation. The other friction plate will continue to rotate, until stopped by the engagement of its ear piece with the stop 14, while the disc 57, 58 and 62 will continue to rotate, in accordance with the operation of the couloring mechanism, until operative engagement between the clutch elements 68 and 69 is discontinued.

By this device, the lead of the carrier rods relative to the operation of the sinkers, which is ordinarily maintained by mechanism associated directly with the carrier rods independent of the friction drive mechanism therefor, is automatically taken care of, to eliminate the usual cumbersome auxiliary members, and the difficulties associated with the synchronization thereof. Thus, as shown in Figs. 8 and 9, with the driver D moving clockwise, and the lever 58 being propelled by the lug 64^b, the arcuate distance between the lug 65^b and the lever 58 corresponds to the amount of couloring effected prior to the actuating of the lever 58 by the ear 64^b.

Although the clockwise travel of the lever 58, and consequently that of the lug 64^b, is controlled by an element of the rod stopping mechanism, as for instance, the stop 71 of the narrowing head N, the corresponding directional movement of the lug 65^b continues until the latter engages the bottom surface of the stop 14. Consequently, if the narrowing mechanism N operates before the couloring of the next stroke, the corresponding carrier rod will be retracted from the position to which it had been moved by its next previous stroke through a distance of two needles, while the lever 58 and lug 64^b will be moved a corresponding distance counterclockwise, whereby the lug 65^b must traverse a distance corresponding to the two-needle narrowing, in addition to the distance above set forth before engaging, and imparting its motion to, the lever 58, and the respective carrier rod. Thus, the decrease in the carrier travel is automatically taken care of, and the lead of the carriers relative to the sinkers is maintained constant, since sinkers of an additional two-needle space are slurred forward, as compared to the previous course, prior to

the engagement of the ear 65^b to the lever 58, and the return movement of the respective carrier rod.

The above-described operation may be better understood from Figs. 14 to 21, inclusive, in which all elements not essential to an understanding of the operation have been removed, and the remaining parts have been so arranged, without regard to actual scale, form or position, as to provide better visualization of the device and its operation.

In Figs. 14 to 17, inclusive, the parts and operation are illustrated in association with a carrier, such as the carrier 2, for laying ordinary yarn courses, such as those in a stocking leg, which are merely laid back and forth between selvedges equidistant from the longitudinal center line of the blank.

In such case, with the carrier rod 2 at the right-hand end of its stroke, against the narrowing stop 11, as seen in Fig. 14, when the actuator rod 26 reciprocates to the left, it turns the gear wheel 52 clockwise through a first stage in which the lugs 64^b and 65^b move from the positions thereof in Fig. 14 to the positions of Fig. 15; this movement being an idle movement, with the lug 64^b merely moving away from the stop 14, and the lug 65^b merely moving away from the lever 58 which is connected to the gear wheel 52 for racking the carrier rod 2.

At the position of Fig. 15, the lug 64^b engages the lever 58 to turn it to the position of Fig. 16; the lug 65^b, at the same time, being moved from its position of Fig. 15, to its position against the stop 14 in Fig. 16.

It is to be noted that, at this stage, Fig. 16, although the lugs 64^b and 65^b, and the lever 58, have all reached the limit of their clockwise movement, and the carrier rod 2 has been moved to position against its left-hand stop 11, the actuator rod 26 has not yet reached the end of its left hand stroke. However, since the actuator rod 26 and its gear wheel 52 are yieldingly frictionally connected to the discs 64 and 65, the rod 26 continues, from its position of Fig. 16, to the end of its left-hand stroke of Fig. 17. Upon starting its return stroke to the right, from the position of Fig. 17, the actuator rod 26 first effects an idle movement of the lugs 64^b and 65^b away from the lever 58 and the stop 14, respectively, the lug 65^b then engaging the lever 58, and the lugs 64^b and 65^b, and the lever 58, moving counterclockwise in unison, until the carrier rod 2 is again racked to the right against its right-hand end stop 71, whereupon the lug 64^b returns to its position of Fig. 14, against the stop 14, and the actuator rod 26 effects a further idle movement to the right, similar to the idle movement thereof, illustrated in Fig. 17.

Note that the positions of the lever 58 in Figs. 14 and 17, respectively, correspond to the positions of the carrier 2, at the right and left hand ends of its stroke, at positions equidistant from the center wale of the stocking blank.

In Figs. 18 to 21, inclusive, the operation of carrier rod 1, as a plating carrier for a heel tab, and the other parts shown, is like that illustrated in Figs. 14 to 17, respectively, except that, in this instance, the lever 58 reciprocates clockwise and counterclockwise between limiting positions, corresponding to the limiting positions of the carrier both at one side of the walewise center of the stocking blank, as illustrated in Figs. 18 and 21, respectively; this result being effected by limiting movement of the carrier rod 1 to the

right, by one of the narrowing stops 71, and to the left by engagement of a lug 1^b on the rod with a plating stop 81, instead of allowing the rod full reciprocation across the blank between portions 5 equi-distant from the walewise center, as determined by the stop 71.

To provide means for engaging the driver D, to and disengaging it from, the driving gear 58, a lever 75 is secured to a shaft 76, which is pivotally 10 mounted in bearing portions of arms 77 projecting from the frame 48, see Fig. 9. Pins 78 maintained by the forked portions of the lever 75, coact with a recessed portion 58^a of the lever 58 relative to the shaft 58, to cause the tooth 68 to either 15 engage or disengage the tooth 69, in accordance with the direction of rotation of the lever 75.

Each of bell cranks 79, provided one for each of the units F¹ to F⁶, respectively, see Figs. 5 and 6, pivotally mounted on a pin 80 at the extended 20 lower portion of the bearing 47, is linked to the lever 75 by a rod 82. The rod 82 is secured at one end, to a stud 83 that is pivotally mounted on the lever 75, and, at the opposite end, extends through a stud 84 supported by the crank 79. A compression spring 85, surrounding the rod 82 between a collar 86, and the stud 84, tends to maintain a 25 collar 87 engaged to the lower side of the stud 84. A tension spring 88, secured to the back beam 15, cooperates with the horizontal arm of 30 the bell crank 79, of the unit F¹, to maintain a follower 89 thereon engaged to an auxiliary variable-link chain 90^a. High links 92 of the chain 90^a, when reaching a position beneath the follower 89, automatically operate the driver D 35 through the above described parts. Similarly, the units F² to F⁶, inclusive, are provided with chains 90^b to 90^h, respectively, including high links 92, like the high links of the chain 90^a, but arranged to have the camming contours of the several 40 chains in accordance with the respective requirements thereof.

The auxiliary variable-link chain 90^a, see particularly Figs. 11, 12 and 13, is maintained between an idler pulley 93 and the sprocket 94, which is secured in position on the main control shaft 95. The latter is intermittently operated by the ratchet structure shown, when a control button 96 on the main pattern device or chain 97, see Fig. 1, is in position to trip the lever 98. 45 When the lever 98 is tripped, it shifts a rod 99 to the right, whereupon a lever 100 is turned clockwise, about its pivotal mounting 102 on the front beam 14, while the end 100^a, which normally supports an arm 103^a of a lever 103, disengages the 50 arm 103^a, as a spring 104, anchored to the back beam 15 by a hook 105, draws a link 106 and permits a follower 107 to engage a control cam 108, Fig. 5.

Coaction, between the follower 107 and the 55 cam 108, rocks the lever 103 relative to a supporting narrowing-lift shaft 109, this action imparting an oscillatory movement to a member 110, loosely mounted on the control shaft 95, whereupon a pawl 112, pivotally mounted on the member 110, racks a ratchet wheel 113 and, consequently, the shaft 95 to which it is secured. This 60 action reengages an adjacent link of the chain 90^a to the roller 89, high links 92 of which automatically operate the bell crank 79. The latter 65 operates the clutch mechanism through the rod 82 and the lever 75, to permit the rack gear 70 to operate the carrier rod through the driver D and the related mechanism above set forth.

Units, such as the units F¹ to F⁶, respectively, 70 for separately operating individual carrier rods,

are spaced at selected points on the machine, see Figs. 3 and 4; the operation of each unit being controlled by an individual auxiliary pattern unit including a variable-link control chain, see particularly Figs. 11, 12 and 13, that is operated 75 by the shaft 95, thereby providing means for automatically and selectively operating the carrier rods.

A knob 116, Fig. 6, is provided to facilitate manual operation of a rod 114. A cam member 10 117, Fig. 10, rotatably mounted on the shaft 95, and connected to the rod 114, has high and low portions 117^a and 117^b that are, respectively, adapted to effect engagement and disengagement of the clutch member, which controls the 15 operation of the corresponding carrier rod. Movement of the rod 114 to the position shown in Figs. 5 and 10, causes a collar 118 to engage the adjacent face of a bracket 115, and the high portion 117^a to coact with an extension 119 of 20 the crank 79 to operate the latter. This action effects engagement between the members 68 and 69, similarly to the manner in which engagement is effected between these members when a high link of the chain 90^a, of the unit F¹, co- 25 acts with the roller 89 to operate the crank 79, and consequently to operate the carrier rod, as above set forth.

However, when the rod 114 is raised, and moved 30 to the left, from the operative position shown in Figs. 5 and 10, so that the collar 118 is moved through the opening in the bracket 115, the spring 88 will lower the horizontal arm of the 35 crank 79 until the extension 119 engages the low surface 117^b, at which position the roller 89 is in contact with a low link of the chain 90^a, whereupon the clutch mechanism operates to disengage the carrier rod from the driving mechanism.

The coaction of the surface 117^a with the extension 119 operates the bell crank 79 and consequently, operates the clutch mechanism in the manner that the latter is operated when a high link 92 coacts with the roller 89; the roller 89 and the extension 119 being carried by the crank 45 79. Consequently, the operation of the crank 79, as effected by its coaction with the surface 117^b, is identical to the movement imparted thereto by engagement of the low links of the chain 90^a with the roller 89; the two mechanisms being provided to permit automatic and 50 manual operation of the clutch member.

In the above described structure, there is but a single linkage, including the link 106, between the cam shaft 10 and the main pattern 55 chain, on the one hand, or at one end of such linkage, and the auxiliary pattern units, including the chains 90^a to 90^h at the other end of the linkage. This linkage not only transmits the driving power of the cam shaft 10 to the 60 chains 90^a to 90^h, but also is directly affected, at a position locally associated with the cam shaft, in accordance with the selective operation thereof by the main pattern chain. In other words, by the arrangement whereby the follower 65 107 is intermittently thrown into and out of operation relative to the cam 108, no part of the linkage to the chains 90^a to 90^h is under constant operation and excessive wear, and, by the single linkage, space is conserved, the number, 70 weight, and cost of parts are reduced, and more effective operation and other advantages are obtained.

The improvements specifically shown and described, by which the above results are obtained. 75

can be modified in various ways without departing from the invention herein set forth and claimed.

I claim:

5. 1. In a straight knitting machine, the combination with knitting mechanism including sinkers, a carrier rod, an actuator rod for the carrier rod, and a coulier-motion mechanism for operating the sinkers and the actuator rod, of means including a rotary clutch for operation, and providing a lost-motion connection, between the carrier and actuator rods and for maintaining the carrier rod in a position of constant lead relative to the operation of the sinkers.

10. 2. In a straight knitting machine, the combination with knitting mechanism including sinkers, a carrier rod, an actuator rod for the carrier rod, and a coulier-motion mechanism for operating the sinkers and the actuator rod, of means disposed, and providing a lost-motion connection, between the carrier and actuator rods for maintaining the carrier rod in a position of constant lead relative to the operation of the sinkers including stop means, a pair of elements 15 frictionally relatively movable with respect to each other and frictionally driven from the actuator rod alternately against opposing sides of said stop means, and a member connected to the carrier rod and having a portion disposed between said elements for alternate movement in opposite directions thereby.

20. 3. In a straight knitting machine, the combination with knitting mechanism including sinkers, a carrier rod, an actuator rod for the carrier rod, and a coulier-motion mechanism for operating the sinkers and the actuator rod, of means disposed, and providing a lost-motion connection, between the carrier and actuator rods for maintaining the carrier rod in a position of 25 constant lead relative to the operation of the sinkers comprising a shaft, means including elements on said shaft for cooperation with said carrier and actuator rods to drive, and be driven by, said rods, respectively, clutching mechanism 30 cooperating with said elements including other elements movable relative to each other, a stationary stop cooperating with said relatively movable clutch elements, and a member connected to the carrier rod cooperating with said mechanism 35 for operating the clutch and cooperating with said clutch elements for providing said constant lead.

40. 4. In a straight knitting machine, the combination with knitting mechanism including sinkers, a carrier rod, an actuator rod for the carrier rod, and a coulier-motion mechanism for operating the sinkers and the actuator rod, of means disposed, and providing a lost-motion connection, between the carrier and actuator rods for 45 maintaining the carrier rod in a position of constant lead relative to the operation of the sinkers comprising means including elements for cooperation with said carrier and actuator rods to drive, and be driven by, said rods, respectively, clutching mechanism 50 cooperating with said elements including other elements movable relative to each other, a stop cooperating with said relatively movable clutch elements, and a second member cooperating with said clutch elements to provide said 55 constant lead.

55. 5. In a straight knitting machine, the combination with knitting mechanism including sinkers, a carrier rod, end stops for the carrier rod, an actuator rod for the carrier rod, and a coulier-motion mechanism for operating the sinkers and

the actuator rod, of stop means, a pair of elements frictionally movable relative to each other and frictionally driven from the actuator rod alternately against opposing sides of said stop means, and a member connected to the carrier 5 rod and having a portion disposed between said elements for alternate movement thereby in opposite directions, said elements operating together in one direction until the carrier rod engages an end stop to stop one of the elements, the 10 other element continuing movement in one direction until stopped by said stopping means, and the actuator rod continuing its operative stroke in corresponding direction after said other element has engaged said stopping means. 15

6. In a straight knitting machine, the combination with knitting mechanism including sinkers, a carrier rod, end stops for the carrier rod, an actuator rod for the carrier rod, and a coulier-motion mechanism for operating the sinkers and 20 the actuator rod, of means disposed and providing a lost-motion connection, between the carrier and actuator rods for maintaining the carrier rod in a position of constant lead relative to the operation of the sinkers including stop means, a pair 25 of elements frictionally driven from the actuator rod alternately against opposing sides of said stop means, and a member connected to the carrier rod and having a portion disposed between said elements for alternate movement in opposite directions thereby, said elements operating together 30 in one direction until the carrier rod engages an end stop to stop one of the elements, the other element continuing movement in said one direction until stopped by said stopping means, 35 and the actuator rod continuing its operative stroke in corresponding direction after said other element has engaged said stopping means.

7. In a straight knitting machine, the combination with knitting mechanism including sinkers, a carrier rod, an actuator rod for the carrier rod, and a coulier-motion mechanism for operating the sinkers and the actuator rod, of means disposed, and providing a lost-motion connection, 40 between the carrier and actuator rods for maintaining the carrier rod in a position of constant lead relative to the operation of the sinkers comprising a shaft, means including elements on said shaft for cooperation with said carrier and actuator rods to drive, and be driven by, said rods, 45 respectively, cooperating lock-clutch elements movably mounted on said shaft, a slip-clutch structure including a member fixed to one of said lock-clutch elements, and a plurality of elements 50 movable relative to said member and frictionally 55 movably related to each other, a stationary stop cooperating with said friction-clutch elements, and a second member connected to the carrier rod movably mounted on said shaft cooperating with said friction-clutch elements to provide said 60 constant lead.

8. In a straight knitting machine, the combination with knitting mechanism including sinkers, a carrier rod, an actuator rod for the carrier rod, and a coulier-motion mechanism for operating the sinkers and the actuator rod, of means disposed, and providing a lost-motion connection, between the carrier and actuator rods for 65 maintaining the carrier rod in a position of constant lead relative to the operation of the sinkers comprising a shaft, means including elements on said shaft for cooperation with said carrier and actuator rods to drive, and be driven by, said rods, respectively, a lock-clutch movably mounted 70

75

on the shaft for cooperation with said elements, a slip-clutch cooperating with the lock-clutch including elements movable relative to each other, a stationary stop cooperating with said slip-clutch elements, and a second member connected to the carrier rod and movably mounted on the shaft for cooperation with said slip-clutch to provide said constant lead.

9. In a straight knitting machine, the combination with knitting mechanism including sinkers, a carrier rod, an actuator rod for the carrier rod, and a coulier-motion mechanism for operating the sinkers and the actuator rod, of means disposed, and providing a lost-motion connection, between the carrier and actuator rods for maintaining the carrier rod in a position of constant lead relative to the operation of the sinkers comprising racks on the carrier and actuator rods, respectively, a shaft, gear wheels fixedly and movably mounted on said shaft for cooperation with said carrier and actuator-rod racks, respectively, cooperating lock-clutch elements movably mounted on said shaft, a slip-clutch structure including a member fixed to one of said lock-clutch elements, and a plurality of elements movable relative to said member and frictionally relatively movably related to each other, a stationary stop cooperating with said friction-clutch elements, and a second member movably mounted on said shaft cooperating with said friction-clutch elements and connected to the carrier rod to maintain said constant lead.

10. In a straight knitting machine, the combination with knitting mechanism including sinkers, a carrier rod, end stops for the carrier rod, an actuator rod for the carrier rod, and a coulier-motion mechanism for operating the sinkers and the actuator rod, of means disposed and providing a lost-motion connection, between the carrier and actuator rods for maintaining the carrier rod in a position of constant lead relative to the operation of the sinkers including stop means, a pair of rotatable elements frictionally movable relative to each other having radial lugs and frictionally driven from the actuator rod to alternately engage one of said lugs against one side of said stopping means and the other lug against an opposing side of said stopping means, and a member connected to the carrier rod and having a portion disposed between said lugs for alternate movement thereby in opposite directions, said elements operating together in one direction until the carrier rod engages an end stop to stop one of the elements, the other element continuing movement in said one direction until stopped by said stopping means, and the actuator rod continuing its operative stroke in corresponding direction after said other element has engaged said stopping means.

11. In a straight knitting machine, the combination with knitting mechanism including sinkers, a carrier rod, an actuator rod for the carrier rod, and a coulier-motion mechanism for operating the sinkers and the actuator rod, of means disposed, and providing a lost-motion connection, between the carrier and actuator rods for maintaining the carrier rod in a position of constant lead relative to the operation of the sinkers comprising racks on the carrier and actuator rods, respectively, a shaft, gear wheels fixedly and movably mounted on said shaft for cooperation with said carrier and actuator-rod racks, respectively, cooperating lock-clutch elements movably mounted on said shaft, a slip-clutch structure

including a member fixed to one of said lock-clutch elements, and a plurality of elements movable relative to said member and frictionally relatively movably related to each other, a stationary stop cooperating with said friction-clutch elements, and a member connected to the carrier rod movably mounted on said shaft cooperating with one of said lock-clutch elements for operating the lock-clutch and cooperating with said friction-clutch elements for providing said constant lead.

12. A straight knitting machine comprising a carrier rod, an actuator for the rod, a connector for connecting the rod to, and releasing it from, the actuator, an auxiliary pattern unit for controlling the connections and releases of the connector, a cam shaft, a cam on the cam shaft, linkage including a follower for movement into and out of operative relation to the cam affecting the operation of said unit, and a main pattern device for controlling said movement of the follower.

13. A straight knitting machine comprising a carrier rod, an actuating member therefor, a rotary friction-slip clutch for connecting the rod to, and disconnecting it from, the actuator, an auxiliary pattern unit including a variable-link chain, means including a bell crank follower element cooperating between the clutch and the chain for controlling the connections and releases of the clutch, and means including a main pattern device for controlling said unit.

14. A straight knitting machine comprising a rotatable cam shaft, an auxiliary control shaft for periodic rotation by the cam shaft, automatic yarn traversing control mechanism including a plurality of movable yarn-carrier rods and a rod-operating mechanism common to the rods, separate rotary clutch devices for connecting the several rods to the common operating mechanism, manually-operable means for engaging the rotary clutch devices to, and disengaging them from, the common operating mechanism, and a pattern chain for operation by the control shaft to selectively control the automatic connection of the rotary clutch devices to the common operating mechanism.

15. In a straight knitting machine, the combination with a cam shaft, knitting mechanism including sinkers, a carrier rod, an actuator rod for the carrier rod, and a coulier-motion mechanism for operating the sinkers and the actuator rod, of means disposed, and providing a lost-motion connection, between the carrier and actuator rods for maintaining the carrier rod in a position of constant lead relative to the operation of the cam shaft, an auxiliary pattern unit for controlling the connections and releases of said lost-motion connecting means, a cam on the cam shaft, linkage including a follower for movement into and out of operative relation to the cam affecting the operation of said unit, and a main pattern device for controlling said movement of the follower.

16. In a straight knitting machine, the combination with a cam shaft, knitting mechanism including sinkers, a carrier rod, an actuator rod for the carrier rod, and a coulier-motion mechanism for operating the sinkers and the actuator rod, of means including a rotary-disc clutch disposed, and providing a lost-motion connection, between the carrier and actuator rods, an auxiliary pattern unit including a variable-link chain and a chain follower connected to the clutch for actuating the same, a cam on the cam shaft, linkage including a follower for movement into and

out of operative relation to the cam affecting the operation of said unit, and a main pattern device for controlling said movement of the follower.

17. A straight knitting machine comprising a carrier rod, an actuator for the rod, a rotary friction-slip clutch for connecting the rod to, and disconnecting it from, the actuator and including cooperating clutch members one of which has an annular portion, a pivoted yoke element for cooperation with said annular portion of said one clutch member to shift the member relative to the other member, an auxiliary pattern unit including a variable-link chain, a bell crank lever element carrying on one arm a follower for the chain, a rod connected between the other arm of the bell crank and the yoke but being longitudinally movable relative to one of said elements, a spring surrounding said connector rod, movement of the bell crank by the chain being transmitted to the yoke through the spring, and a main pattern device for controlling the operation of the auxiliary follower unit.

18. A straight knitting machine comprising a carrier rod, an actuator for the rod, a rotary friction-slip clutch for connecting the rod to, and disconnecting it from, the actuator and including cooperating clutch elements one of which has an annular portion, a pivoted yoke for cooperation with said annular portion of said one clutch element to shift said element relative to the other, 10 an auxiliary pattern unit including a variable-link chain, a sprocket wheel for the chain and a shaft for the wheel, a bell crank lever carrying on one arm a follower for the chain, a link connection between the other arm of the bell crank and 15 the yoke, a ratchet wheel on said shaft, a pawl for actuating the shaft and the sprocket wheel through the ratchet wheel, and a main pattern device for controlling the operation of the auxiliary pattern unit.
